CIRCUIT BREAKER

John W. May, Pittsburgh, and William H. Stuellein, Pitcairn, Pa., assignors to Westinghouse Electric & Manufacturing Company, East Pittsburgh, Pa., a corporation of Pennsylvania

Application May 6, 1941, Serial No. 392,048

13 Claims. (Cl. 200—106)

This invention relates to circuit breakers and more particularly to circuit breakers of the type which are tripped instantaneously in response to overload currents above a predetermined value and after a time delay on lesser overloads.

One object of the invention is to provide a circuit breaker with an improved trip device of simple and inexpensive construction which is operable to trip the breaker instantaneously upon the occurrence of overloads above a predetermined magnitude and after a time delay for continuing overloads up to said predetermined values.

Another object of the invention is the provision of a circuit breaker having an improved sucker type time delay device in which the time delay elements are self-aligning.

Another object of the invention is the provision of a circuit breaker having an improved time delay device including a pair of engageable elements, one of which is mounted to permit automatic alignment thereof with the other element and which is rotatable to vary the amount of time delay.

Another object of the invention is the provision of a circuit breaker having an improved trip device provided with a time delay device of the suction disc type wherein one of the discs is adjustable to adjust a magnetic air gap and the other of said discs is adjustable to vary the duration of the time delay.

Another object of the invention is the provision of a circuit breaker having an improved trip device operable instantaneously in response to overloads above a predetermined value, a time delay device to delay tripping in response to overloads below the predetermined value and adjustable means to vary the instantaneous tripping point.

Another object of the invention is the provision of a circuit breaker having a trip device provided with an improved sucker type time delay device said time delay device being removably supported on the trip device.

Another object of the invention is the provision of a circuit breaker with a trip-device having an improved calibrating and adjusting means.

The novel features that are considered characteristic of the invention are set forth in particular in the appended claims. The invention itself, however, both as to structure and operation, together with additional objects and advantages thereof, will be best understood from the following detailed description of one embodiment

ment thereof when read in conjunction with the accompanying drawings, in which:

Figure 1 is a vertical sectional view through the center pole of a three pole circuit breaker embodying the features of the invention;

Fig. 2 is a fragmentary sectional view taken substantially on the line II—II of Fig. 1;

Fig. 3 is a vertical sectional view through the trip device taken substantially on line III—III of Fig. 2 and showing the trip mechanism in instantaneously tripped condition;

Fig. 4 is a vertical sectional view similar to Fig. 3, but showing the trip device in condition when tripped after a time delay;

Fig. 5 is a detail view in elevation of the time delay device;

Fig. 6 is a bottom view of the upper suction disc showing the suction areas; and

Fig. 7 is a horizontal sectional view through the time delay device taken on line VII—VII of Fig. 4 and looking in the direction of the arrows. Fig. 7 shows the suction areas of the lower suction disc.

Referring to Figure 1 of the drawings, 11 is a base plate of insulating material upon which the three pole circuit breaker is mounted. A casting 13 and a cover plate 15 may be provided to enclose the circuit breaker mechanism, the casting and cover plate being shown in dot and dash lines.

The main frame which supports the breaker operating mechanism comprises a pair of parallel frames 17 (only one being shown) rigidly joined by a cross member 19 which is secured to the central portion of the base 11 by means of bolts 21 and 23. The frames 17 are also connected by a cross member 25 at their outer ends to form a rigid framework. The bolts 23 project through the cross member 19 and serve as means for securing a connector 27 of conducting material to the cross member 19.

A pivot 29 extends through a hole in the casting 27 and pivotally supports a forked contact arm 31 for the center pole of the breaker. The forks (only one being shown) of the contact arm 31 are disposed one on each side of the casting 27. The contact arms for the two outer poles (not shown) are mechanically connected for movement with the central contact arm 31, as will be hereinafter described so that this central contact arm forms the common switch member and support for the movable contacts of all three of the poles. The free end of the contact arm 31 pivotally carries a main contact 33 and an arcing contact 35 adapted to cooperate

respectively with stationary contacts 39 and 37 secured to a contact member 41. The contact member 41 is secured to the base 11 by means of bolts 43, the member 41 being bent at right angles and passing through the base to form a terminal conductor 45.

The contact 33 is electrically secured on a contact member 47 pivoted on a pin 49 supported in projections 51 (only one being shown) of the contact arm 31. A spring 53 compressed between a spring seat on the contact arm 31 and a spring seat in the contact member 47 provides pressure for the contacts 33 and 39.

The arcing contact 35 is mounted on a contact member 55 pivoted on a pin 57 mounted in projections 59 of the contact arm. A rod 61 pivotally connected to the contact member 55 slidably projects through an opening in the contact arm 31. A spring 63 surrounding the rod 61 is compressed between the contact arm 31 and a flange 65 on the rod 61 to provide contact pressure for the arcing contacts 35 and 37.

The contact arms for the two outer poles of the breaker, which are disposed on opposite sides of the center pole and main frame, are mechanically connected to the center pole contact arm for movement therewith as a unit by means of a tie bar 67 which extends across the three poles of the breaker. The tie bar 67 is surrounded by a sheath of insulating material 69 to insulate the several poles and is secured to each of the contact arms by means of a clamp and a bolt 71.

The terminals, conductors, contact means and contact arms of the two outer poles (not shown) are identical in construction to the corresponding elements of the center pole except that the contact arms of the two outer poles do not have any lower forked or pivoted portion as in the case of the center pole contact arm, and conducting blocks of the outer poles corresponding to the center pole block 27 are bolted directly to the base 11.

When the contact arm 31 is rotated clockwise, as will hereinafter be described, to open the contacts, the springs 53 and 63 rock the contact members 47 and 55, respectively, counterclockwise about their pivot pins. This movement of the contact member 47 is limited by a projection 73 thereon striking the body of the contact arm 31 and the movement of the contact member 55 about its pivot is limited by a nut 75 on the end of the rod 61 striking the contact arm. The arrangement of the parts is such that the contacts 33-39 open before the arcing contacts 35-37.

The arc incident to the rupture of the current is dissipated by arc extinguishers 76 of which there are three, one associated with each pole of the breaker. Each of these arc extinguishers comprises, generally, a stack of slotted plates disposed adjacent the path of travel of the arcing contacts 35. The plates of the extinguisher cause the arc to be drawn toward the ends of the slots and into the stack of plates resulting in the breaking up of the arc into a plurality of small arcs and causes said arcs to be quickly cooled and extinguished.

The electrical circuits for the several poles of the breaker are essentially the same, each circuit extending from the terminal 45 through the contact member 41, contacts 33-39, the contact member 47, a flexible shunt conductor 79 connecting the contact member 47 and the casting 27, and a conductor 81 secured to said casting 27. The conductor 81 extends downwardly from

the casting and is bent at right angles to project through the base 11 forming a terminal 83 which, together with the terminal 45, serves to connect the breaker in an electrical circuit. The circuit through the arcing contacts extends from the terminal 45 through the arcing contacts 37-35, and a flexible shunt conductor 77 to the main contact member 47 and thence through the flexible shunt conductor 79 and block 27 to the lower terminal 83.

A spring 85 having one end connected to the contact arm 31 near its free end, and its other end hooked over a fixed pivot pin 87 supported in the frame 17 biases the contact arm 31 in a clockwise direction toward open position. Under normal circuit conditions, the contact arm 31 is releasably restrained in closed circuit position (Fig. 1) by means of a linkage and toggle arrangement described as follows:

A lever 89 (Fig. 1) pivotally mounted on a fixed pivot comprising a shaft 91 supported in bearings in the main frame 17, is connected by a main operating toggle comprising links 93 and 95 to the contact arm 31. The toggle links 93 and 95 are pivotally connected by a knee pivot pin 97, and the link 95 is pivoted on a pin 99 supported in the forks of the contact arm 31. The link 93 is pivotally connected to the lever 89 by a pivot pin 101.

A link 103 connects the lever 89 to one arm of a lever 105 pivoted on the fixed pivot 87. The other arm of the lever 105 is pivotally connected to one end of a toggle link 107 having its opposite end pivotally connected to a toggle link 109 by a knee pin 111, the toggle link 109 being pivoted on a fixed pivot 113 supported in the frames 17. The link 95 comprises a pair of links joined by a cross bar 115, which cooperates with an extension of the link 93 to limit upward movement of the main operating toggle. The lever 89 comprises a pair of levers rigidly jointed by a cross bar 117, and the link 103 and the lever 105, each comprises a pair of members joined by yokes substantially as illustrated. The toggle link 107 comprises a pair of links joined by a yoke 119 having a turned out portion 121, the purpose of which will be described later. The toggle link 109 comprises a pair of links joined at their ends adjacent the fixed pivot 113 by a cross member 123 having formed portions 125 and 127 thereon.

In the closed contact position of the contact arm 31, the toggle 93-95 is overcenter above a line drawn through the centers of the pins 99 and 101 and the toggle comprising the link 93 and the lever 89 is overcenter above a line drawn through the center of the knee pin 97 and the fixed pivot 91, the overcenter movement of said toggles being limited by the end of the link 93 engaging the cross bar 115 joining the links 95. In this position, the lever 89 is biased in a clockwise direction by the spring 85 but is prevented from rotation by the fact that the toggle 107-109 is slightly overcenter to the left (Fig. 1) of a line joining the centers of the fixed pivot 113 and the point of connection of the toggle link 107 and the lever 105 being restrained in this position by a spring 128 tensioned between the yoke 119 and the fixed pivot 113. The overcenter position of the toggle 107-109 is adjustably determined by the formed portion 125 striking an adjusting screw 129 in the cross member 25 joining the frames 17.

It can be seen, therefore, that the linkage is effective in its overcenter position to maintain

the contacts in closed position. The toggle 107—109 is adapted to be moved to collapsed position to trip the breaker and cause opening of the contacts in response to overload currents by a trip device indicated generally at 138 (Fig. 1) acting through a trip rod 135. The trip device, when actuated in response to abnormal circuit conditions, is adapted to thrust the rod 135 upwardly, the upper end of said rod striking the portion 121 of the cross member 123, rocks the toggle 109 clockwise about its fixed pivot 113 causing collapse of the toggle and linkage.

The trip rod 135 is surrounded by a shunt trip electromagnet enclosed in a casing 138 secured to the frame 17, which electromagnet may be energized by a shunt circuit or by a manually controlled switch to operate the trip rod 135 in a manner well known in the art.

When the toggle 107—109 collapses, it permits the spring 85, acting through the contact arm 31 and the toggle 93—95, to rock the lever 89 clockwise about its pivot, which movement is transmitted through the link 103 to rock the lever 105 clockwise. The toggle 93—95 does not immediately break overcenter but travels as a unitary linkage with the contact arm 31 and the lever 89 until the movement of the contact arm 31 is arrested by the tie bar 67 striking a portion 137 of the frame structure 17. By the time knee pin 97 of the main toggle has passed below the center line 99—101 the weight of the linkage and parts causes the main toggle to collapse and the lever 89 and linkage 103, 105, 107 and 109 to be automatically reset to their normal position as shown in Fig. 1.

As soon as the toggle 93—95 collapses the spring 128 aids in restoring the toggle 107—109 to its overcenter position and in resetting the lever 105, link 103 and lever 89 to their normal position (Fig. 1). The toggle 93—95 remains in collapsed condition until the breaker is reclosed which may be accomplished either electrically or manually.

The contacts are reclosed either manually, or automatically. An electric motor unit indicated generally at 139 (Fig. 1), mounted on a bracket 140 secured to the main frame 17 is provided to automatically reclose the contacts. To close the contacts manually a handle 141 rotatably mounted in a frame 143 of insulating material secured to the main frame 17, is rotated in clockwise direction.

Pivotedly mounted on the shaft 91 is a closing lever 145 comprising a pair of levers joined at their outer ends by a cross member 147 and at their inner ends by a cross bar 149. A link 151, adapted to be thrust downwardly upon clockwise closing movement of the handle 141, is notched at its lower end and engages an hour glass-shaped roller 153 pivotally mounted on the cross member 147. A roller 155 is rotatably mounted on a rod 157 supported in spaced projections 158 on the cross member 149.

The downward movement of the link 151 rocks the closing lever 145 clockwise about its pivot. At this movement the roller 155 engages the collapsed toggle 93—95 and moves this toggle to its overcenter position rotating the contact arm 31 counterclockwise against the tension of the spring 85 to close the contacts. When the handle 141 is released, a spring 159 tensioned between the frame 17 and the closing lever 145 rocks said closing lever counterclockwise to normal position, thrusting the link 151 upwardly and returning the handle to its neutral position.

The circuit breaker may also be closed through the agency of the motor 139 which may be energized in a manner well known in the art. The motor unit includes a crank disc 156 driven by the electric motor through a reduction gear. The crank disc carries a crank roller 160 which is adapted to engage the curved surface 162 of a plate 164 secured to the side of the closing lever at its outer end. When the motor is energized the crank roller 160 engages the curved surface 162 and rotates the closing lever in a clockwise direction to close the breaker after which the crank roller passes out of engagement with the surface 162 and the motor is deenergized by a suitable limit switch.

The breaker may be tripped manually by rotating the handle 141 through a small angle in a counterclockwise direction from its neutral position. A projection (not shown) on the handle mechanism, during such tripping movement, engages the previously described portion 121 of the yoke 119 to cause collapse of the tripping toggle 107—109 and opening of the contacts.

The construction of the circuit breaker as thus far described is substantially the same as that fully disclosed in the copending application of John W. May and Ture Lindstrom, Serial No. 391,625, filed May 3, 1941, and assigned to the assignee of the present invention.

The tripping rod 135 is also operated by any one of the trip devices 133, in response to overload conditions in the circuit controlled by the breaker, there being one trip device for each of at least two poles of the breaker. Since the trip devices are all alike only one will be described.

Each of the trip devices 133 (Figs. 1 to 4, inclusive) includes a laminated U-shaped magnet core 161 and a frame comprising a pair of parallel plates 163 joined at their outer ends by a yoke 165. The plates 163 are bent at right angles at their inner ends to form mounting feet 167 abutting against the magnet core 161 and bolts 169 pass through openings in the mounting feet 167, the magnet core 161 and the base 11 to secure the plates 163 and the magnet core 161 to the base, a spacer 171 of insulating material being provided between the magnet core and the base.

The core 161 is U-shaped and the conductor 81 is disposed between the two legs thereof. The flow of current through the conductor serves to energize the core. A trip lever comprising a pair of parallel joined levers 173 is pivotally supported on a rod 175 supported in the plates 163. At their outer ends, the trip levers 173 are joined by a yoke 177 and a pair of laminated armatures 179 is secured to the ends of the levers 173 adjacent the legs of the magnet core 161.

Each of the yokes 177 carries an adjustable screw 181 locked in its adjusted position by a lock nut 183. Upon operation of the trip lever 173 in response to an overload in the circuit of its corresponding pole, the screw 181 strikes an arm 185 on a trip bar 187 rotatably mounted in a bracket 189 secured to the casing 138 (Fig. 1), and rocks said trip bar in a clockwise direction (Fig. 1). The trip bar 187 extends transversely across all of the poles and is provided with an arm 185 for each pole. One of the arms 185 is in alignment with the trip rod 135 and upon clockwise movement of the trip bar 187, the rod is thrust upwardly to trip the breaker.

The adjusting screw 181 provides for uniform calibration of all trip units when there might be

slight variations in the mounting of the trip devices.

The trip lever 173 is biased against tripping movement by a pair of springs 191 having their upper ends attached to the outer end of the yoke 177 and their lower ends connected to an adjustable plate 193. A screw 195 having a thumb nut 197 on the lower end thereof bearing against a formed over portion 199 of the yoke 165 cooperates with the plate 193 for the purpose of adjusting the tension of the springs 191. The yoke 165 is also provided with spaced extensions 201 to the sides of which is adjustably secured a U-shaped scale plate 203 by means of screws 204 passing through elongated slots 206 in the plate 203. The spring plate 193 carries a pointer 205 projecting through a vertical slot 207 in the scale plate 203 which bears a scale indicating the tripping current values of the breaker.

The trip device 133 is provided with a dual overload device which provides a time delay for tripping the breaker on overloads below a predetermined value, for instance, 1000% of rated load, but which permits instantaneous tripping on overload above 1000% of normal.

This device includes a dashpot of the suction disc type removably mounted on the yoke 165 of the frame 163 (Figs. 1, 3 and 4). A disc 209 is secured on the lower end of a rod 211 by means of a screw thread, and a pin 213 normally prevents rotation of the disc 209 on the rod. The rod 211 passes through an opening in a circular plate 215 secured to the yoke 165 by screws 217, said plate serving as a guide for the rod. The enlarged upper end 219 of the rod 211 is provided with an open slot 221 engaging a rod 223 mounted on and extending between the sides of the tripping lever 173. The enlarged end 219 of the rod 211 is slidable in a cylinder 225 rotatably supported on the rod 223 and having its lower end formed into an inwardly extended flange 227. A spring 229 is compressed between the shoulder formed by the enlarged end 219 of the rod 211 and a washer 231 surrounding the rod 211 and seated on the flange 227.

Mounted between the plate 215 and the yoke 165 and securely held in place by the screws 217 is a spring disc 233 having three downwardly extending clips 235 substantially equally spaced about its periphery (see also Fig. 5). An annular gasket 237 (Figs. 3 and 4) is mounted between a shoulder of the plate 215 and the spring member 233. The spring clips 235 are formed in such a manner as to cooperate with annular projections 239 on the periphery of a cup-like dash pot 241 and firmly support the dash pot. The lower surfaces of the projection 239 are beveled and the spring clips 235 are tensioned inwardly into engagement with the beveled surfaces. The force exerted by the spring clips 235 presses the dash pot 241 into engagement with the gasket 237 to form a seal for preventing oil leakage.

The dash pot 241 is of moulded insulating material and serves to loosely support a suction disc 243. This disc has a concave bearing surface and rests on a substantially spherical projection 245 moulded integral with the bottom of the dash pot. A shoulder screw 247 in the projection 245 permits spherical movement of the suction disc 243 on the projection to provide for automatic alignment of the suction surface of said disc with the suction surface of the upper suction disc 209, when the disc 209 comes into contact with the disc 243.

The dash pot is removable by rotating it to

bring spaces 249 (Fig. 5) between the projection 239 into alignment with the spring clips 235 and then lowering the pot. The dash pot is installed by aligning the spaces 249 with the spring clips 235, pressing it upwardly against the gasket 237 and then rotating the dash pot to engage the projections 239 with the spring clips 235.

Referring to Figures 6 and 7, the upper suction disc 209 (Fig. 6) is provided with two raised suction surfaces indicated at 251, and the lower suction disc 243 (Fig. 7) is provided with two raised suction surfaces 253 of substantially the same shape and area as those of the upper disc. When the suction surfaces of the two discs 209 and 243 are in alignment, the suction force and consequently the time delay is 100% and when the suction surfaces 253 of the disc 243 are aligned with the depressed surfaces between the suction surfaces of the disc 209, the retarding suction force and consequently the time delay is substantially zero.

The bottom suction disc 243 may be rotated by rotating the dash pot to vary the suction force of the discs and consequently the time delay. For this purpose, projections 255 moulded in the bottom of the dash pot 241 engage openings in the lower disc 243. Rotation of the dash pot 241 through the agency of the projection 255 causes rotation of the disc 243 relatively to the disc 209.

A scale 257 on the periphery of the dash pot is calibrated to indicate 0% to 100% of overlap of the suction surfaces 251 and 253 (Figs. 6 and 7), or 0% to 100% of suction force. One of the spring clips 235 is extended downward as at 259 (Fig. 5) to serve as an index or pointer and operates with a series of notches 261 molded in the periphery of the dash pot 241 to align and retain the dash pot and the suction disc 243 in the adjusted position.

The dash pot 241 is filled with oil or other viscous liquid to approximately the level indicated by dotted lines (Figs. 3 and 4). Under normal current conditions, the suction surfaces 35 of the discs 209 and 243 are pressed together and the oil squeezed out from between the suction surfaces by the downward force exerted by the springs 191.

Referring now to Fig. 1, the movable parts of the trip device 133 are shown in the position they assume under normal circuit conditions. Current of rated value flowing in the circuit of the breaker causes slight energization of the magnet 161 but the pull of the magnet under 55 normal condition is not sufficient to overcome the tension of the springs 191.

Upon the occurrence of overloads up to a predetermined value, for example, up to 1000% of normal rated current, the magnet 161 attracts the armatures 179 with a force sufficient to overcome the tension of the springs 191 and acting through the cylinder 225 applies pressure to the spring 229. This pressure is transmitted by the spring 229 and applied to the enlarged end 219 of the rod 211 in an upward direction, and after a time delay, breaks the suction between the discs 209 and 243. The magnet 161 moves the armature to attracted position rocking the tripping lever 173 sharply counterclockwise to cause tripping of the breaker in the manner previously described.

Obviously the higher the value of the overload current the greater will be the magnetic pull on the armature 179 and the greater will be the force exerted to separate the suction discs, which

results in tripping the breaker after shorter time delays as the value of the overload increases. This is true up to overloads of a predetermined value, approximately 1000% of rated current.

Upon the occurrence of an overload above the predetermined value or a short circuit, the magnetic pull is sufficiently great to cause instantaneous tripping of the breaker. In this case, the tripping lever 173 is operated instantaneously compressing the spring 229 without waiting for the force applied on the rod 211 to break the suction between the suction discs. The parts are shown in the instantaneously tripped position in Figure 3.

The springs 191 return the tripping lever 173 to normal position as soon as the circuit is opened and the magnet 161 deenergized.

The open air gap at the armature 179 is determined by the upper sucker disc 209 engaging the disc 243. The air gap may be adjusted by removing the pin 213 and rotating the disc in either direction at least 180°. This moves the disc 209 axially on the rod 211 and consequently decreases or increases the air gap depending on the direction the disc is rotated. The pin 213 is then reinserted to lock the disc in its adjusted position.

The dash pot and its connections to the tripping lever 173 may be readily removed from the trip device by removing the pin 223 and the two screws 217 when it is desired to instantaneously trip the breaker on all overloads. When the pin 223 and the screws 217 have been removed the time delay device may be removed by lowering it, the cylinder 225 passing through the enlarged opening in the yoke 165. With the time delay device removed the open air gap at the electromagnet is adjustably determined by means of an adjusting screw 263 (Figs. 1, 3 and 4) in the yoke 165. A lock nut 265 is provided to lock the adjusting screw 263 in its adjusted position.

The circuit breaker is trip free under all conditions, that is the contacts are capable of being opened upon operation of the trip device irrespective of the position of the closing lever, since the assemblage of movable contacts will move to open position when the lever 89 is released even though the main operating toggle is prevented from collapsing by the closing lever.

Certain features disclosed but not claimed in this application are disclosed and claimed in the aforementioned copending application of John W. May and Ture Lindstrom, Serial No. 391,625, filed May 3, 1941.

Having described the preferred embodiment of the invention in accordance with the patent statutes, it is to be understood that various changes and modifications may be made in the structural details disclosed without departing from some of the essential features of the invention. It is, therefore, desired that the language of the appended claims be given a reasonably broad interpretation as the prior art permits.

We claim as our invention:

1. A trip device for a circuit breaker including an electromagnet operable in response to predetermined circuit conditions, and a time delay device comprising separable suction members for at times delaying operation of the trip device, one of said suction members being loosely supported to permit automatic alignment of said suction members, said loosely supported suction member being rotatable relative to the other suction member to vary the time delay of the trip device.

2. A trip device for a circuit breaker including means operable in response to predetermined circuit conditions, time delay means comprising separable suction members for at times delaying operation of the trip device, and a pot in which said suction members are disposed, one of said members being movably supported by the pot, said pot having a substantially spherical surface engaging a circular recess in the central portion of said one suction member to permit automatic alignment of said separable suction member, said pot being rotatable to adjust one of the separable members to vary the time delay of the trip device.

3. A trip device for a circuit breaker including 15 a trip member, an electromagnet responsive to predetermined circuit conditions for operating the trip member, a time delay device including a reciprocably movable member operatively related to the trip member, a suction member rigidly mounted on the reciprocable member, a second suction member cooperating with the first suction member to delay operation of the trip member, and a pot in which said suction members are disposed, said second suction member being mounted in said pot for universal tilting movement to permit automatic alignment of said second suction member with the first suction member, said pot and said second suction member being rotatable to vary the time delay of the trip device.

4. A trip device for a circuit breaker including 20 a trip member, electromagnetic means operable in response to predetermined circuit conditions to operate the trip member, and a time delay device operatively connected to said trip member for at times delaying operation of the trip device. 25 said time delay device comprising a suction member movable with the trip member, a second suction member cooperating with said first named suction member, and a pot having a bearing for movably supporting said second suction member to permit alignment of the second suction member with the first suction member, said pot and said second suction member being rotatable to vary the time delay of the trip device.

5. A trip device for a circuit breaker including 30 a trip member, electromagnetic means responsive to overload circuit conditions to operate the trip member, a member pivoted on the trip member and movable therewith, a time delay device 35 movably mounted on said trip device and including a pot for delaying operation of the trip member in response to overload currents below a predetermined value, a reciprocable member operatively connected to the pot and separably engageable with the trip member, and resilient means 40 between the pivoted member and the reciprocable member to permit instantaneous operation of the trip member in response to overload currents above said predetermined value.

6. A trip device for a circuit breaker comprising 45 a pivoted trip member and an electromagnet for operating said trip member, a rod reciprocably movable with said trip member, retarding means for at times delaying operation of the trip member comprising a suction member rigidly attached to the rod, said suction member having segmental suction surfaces, a second suction member having segmental suction surfaces cooperating with the suction surfaces of the first suction member 50 to retard operation of the trip member, and support means comprising a pot having a bearing for supporting said second suction member to permit movement thereof relative to said pot to align said suction members, said pot having 55 means engaging the second suction member for

rotating said suction member relative to the first suction member to vary the time delay.

7. A trip device for a circuit breaker comprising a trip member, a spring biasing said trip member against tripping operation, and an electromagnet operable in response to overload circuit conditions to operate the trip member, a member movable with the trip member, retarding means comprising a pair of suction members having raised suction surfaces thereon one of said suction members being mounted on said movable member, a pot having a bearing for movably supporting the other suction member to permit automatic alignment of said suction members, said pot being rotatable to adjust the suction surfaces of the suction members to vary the time delay on overloads below a predetermined value, resilient means between the movable member and the trip member to permit instantaneous operation of said trip member on overloads above the predetermined value independently of the suction members, and means to vary the minimum trip current characteristic of the trip device.

8. A trip device for a circuit breaker including a trip member, an electromagnet responsive to abnormal circuit conditions for moving the trip member, and a time delay device including a reciprocably movable member, a suction member on said reciprocable member and adjustable on said member to vary the open air gap of the electromagnet, and another suction member cooperating with the first suction member to delay operation of the trip member, said other suction member being loosely mounted to permit automatic alignment with said first member and being rotatable to vary the time delay of the trip device.

9. A trip device for a circuit breaker including a trip member, means comprising a frame for supporting the trip member, means responsive to predetermined circuit conditions for operating the trip member, a time delay device comprising a unitary structure removably supported on the trip device, said time delay device including a pair of suction members, one of said suction members being operatively related with the trip member for at times delaying operations of said trip device, a pot for movably supporting the other of said suction members, and means supported on the frame comprising a plurality of spaced spring members disposed to engage spaced projections on the pot to removably support said pot on the trip device.

10. A trip device for a circuit breaker including a trip member, means responsive to predetermined circuit conditions to operate the trip member, and a time delay device including a pair of suction members, a reciprocable member supporting one of said suction members, said recip-

rocable member having a slot therein separably engaging the trip member, a member pivotally supported on the trip member at all times movable therewith, and a compression spring between the reciprocable member and said pivotally supported member to permit operation of the trip member independently of the reciprocable member.

11. A trip device for a circuit breaker including a trip member, electroresponsive means operable in response to predetermined overload current conditions to operate the trip member, a time delay device for at times delaying operation of the trip device in response to overload currents below a predetermined value, a member pivotally supported on the trip member at all times movable therewith, a reciprocable member connected to the time delay device and separably engageable with the trip member, and a spring between the pivotally supported member and the reciprocable member, said spring acting to permit instantaneous operation of the trip device independently of the time delay device to trip the breaker in response to overload currents above a predetermined value.

12. A trip device for a circuit breaker operable in response to predetermined circuit conditions, said trip device including a frame, a pivoted armature, an electromagnet for operating said armature, a movable member, a spring between said movable member and the armature biasing said armature against operation, a headed screw bearing against a portion of the frame and having a threaded portion threadedly engaging said movable member for adjustably moving the movable member, a pointer on the movable member, and a scale plate adjustably supported on the frame, said plate being provided with a guide slot for the pointer.

13. A trip device for a circuit breaker including a frame, an armature pivotally supported on said frame, an electromagnet for operating the armature, a time delay device comprising a dash pot operatively connected to the armature for delaying operation of the trip device in response to overload currents below a predetermined value, said dash pot being rotatably adjustable to vary the time delayed tripping point of the trip device, a movable member, a spring between said movable member and the armature biasing said armature against operation, a screw threadedly engaging said movable member for adjustably moving the movable member to thereby adjust the tension of said spring, a pointer on the movable member, and a scale plate adjustably supported on the frame, said scale plate having a guide slot for receiving the pointer.
